UNITED STATES PATENT OFFICE.

GUSTAVE BAUCHE AND HENRI BAUCHE, OF RHEIMS, FRANCE.

MACHINE FOR NAPPING TEXTILE FABRICS.

SPECIFICATION forming part of Letters Patent No. 393,605, dated November 27, 1883.

Application filed March 30, 1883. Serial No. 269,026. (No model.) Patented in France September 26, 1887, No. 186,067, and in England March 16, 1888, No. 4,102.

To all whom it may concern:

Be it known that we, GUSTAVE BAUCHE and HENRI BAUCHE, citizens of France, residing at Rheims, in the Department of the Marne, France, have invented a new and useful Improvement in Machines for Napping Textile Fabrics, (for which we have obtained French Patent No. 186,067, dated September 26, 1887, and English Patent No. 4,102, dated March 16, 1888,) of which the following is a specification.

This invention relates to machinery for napping (forming or raising a pile or nap on) all sorts of fabrics of wool, cotton, or other textile materials. It enables the rough action of the ordinary cards or metal teazles to be avoided, and insures a very regular working in which the fabrics are not broken, whatever may be their character, their lightness, or their power of resistance.

In the accompanying drawings, Figure 1 is a view in elevation with one of the side frames removed of a napping-machine containing the present improvements. Fig. 2 is an end view partly in section; Fig. 3, an edge view of the parts in which the invention principally resides, and Fig. 4 is a detail view.

The cards 1, termed "workers," are placed in revolving carriers, of which four (lettered B', B², B³, and B⁴) are shown. They are arranged in series of three to each carrier; but their number, as also the number of carriers, can be increased or diminished at will. Each worker 1 is journaled in bearings in the heads of the appropriate carrier. The carriers are journaled in bearings in the side frames of the machine and are driven by any ordinary or suitable gearing (belts, for example)—which is not shown, as it forms no part of the invention and can be applied by any competent mechanic.

The fabric to be napped is represented by the broken line *a*, and is drawn in the direction of the arrows, passing over the guide-rollers *b b' b''*, and being by them held in proximity to the carriers B' B² B³ B⁴ of the workers. The means employed to feed the fabric and keep it stretched are not material to the invention. They may be of any known or suitable description. As shown, however, there is a wooden roller, *P*, over which the fabric *a* is drawn, and it is provided with a

brake in the form of a leather strap, *P'*, which can be tightened or loosened by means of the screw *R* and its nut, so as to increase or diminish the tension on the stuff.

55

Q is a toothed wheel at the end of a shaft, *Q'*, which carries a rod, *V*, at the ends of the arms *V'*, and there is a pawl, *S*, which engages the wheel *Q* and holds the shaft *Q'* and rod *V* stationary. The fabric is drawn around the rod *V* and a roller on the shaft *Q'*, and by adjusting the position of the rod *V*, which is effected by releasing the pawl *S* and turning the wheel *Q*, the tension which is exerted on the fabric can be regulated.

65

J H are the drawing or feed rollers, and *F* a pressure-roller, all of which are or may be of ordinary construction and operation. The drawing or feed rollers deliver the fabric to a vibratory arm, *M'*, (as common in similar mechanism,) for laying the fabric in folds, and this arm *M'* is reciprocated by a crank-wheel, *O*, through a pitman, *M*.

70

As shown, the roller *J* is driven from a belt-wheel, 15, through a spur-gear, 16, rotating with said belt-wheel and meshing with the spur-gear 17 on the roller *J*, and the roller *H* is driven by frictional contact with roller *J*.

75

The fabric to be napped is first acted upon by the workers or cards 1 on one side of the carrier B'. Then it descends on the other side of the same carrier, to be acted upon a second time by the same set of cards. It is then acted upon in succession by the workers or cards 1 of the carriers B², B³, and B⁴, all the carriers being rotated, as before described, and carrying around with them their respective workers 1, so as to draw them successively over the fabric. It is in the mounting of these workers on their carriers that the invention mainly resides.

80

Referring to Figs. 2, 3, and 4, the axles *A* of the workers or carding-drums have pillow blocks or bearings 2 combined with springs *K*, which force the blocks or bearings against the axles, so as to give a yielding resistance to the rotation of the workers. These springs, which are by preference leaf-springs in the form of endless bands, curved as shown—one for each end of the carrier—surrounding the axis of said carrier and forming an elastic support common to all the journals, as shown in the

85

90

95

100

drawings, perform their function by giving way to the resistance of the fabric in contact with the metal cards of the workers, which engage the stuff to be napped solely by virtue of the elastic force of the said springs, a force which can be varied according to the fabric treated. The workers thus form yielding carding-drums, which can be rotated on their own axes by the contact with the fabric to be napped.

10 The blocks 3 are out of contact with the blocks 2, so as not to prevent the latter from being pressed against the axles by the springs K, and they are confined by the plates 6, fastened by screws to the circular head of the carrier. In

15 this outer block is or may be formed a lubricant-chamber, 9, in the bottom of which cotton may be placed. Two conduits, 10, extend from this chamber or reservoir 9 to the axle A of the worker. The inner block, 2, has a

20 screw-threaded stud, 5, on which is screwed the nut 4, that rests on the spring K. The nuts 4 have teeth or cogs on their peripheries, and those at the same end of each set of workers are engaged by the gear 7, so that by turning

25 said gear to the right or left each nut will be screwed off or on its stud 5, and the tension of the spring K consequently increased or diminished.

The pressure with which the block 2 is held

30 against the axle A varies, of course, with the tension of the spring K and permits the worker to turn with greater or less freedom; or, in other words, the effect of the brake on the worker is changed as may be required. The

35 metal teeth of the cards will penetrate into the fabric, more or less, according to the resistance offered, without permitting the said fabric to be torn.

The gear 7 can most easily be turned by a

40 pin inserted into one of the holes 8. (Shown in Fig. 3.)

At the moment when, by the rotation of the carriers B' B² B³ B⁴, a worker, 1, comes into contact with the fabric it is subjected, by reason

45 of such contact, to a pressure which tends to bend the spring, so that the working-teeth act upon the material only to the extent required to nap without injuring the fabric. It will, of course, be understood that by increasing or

50 diminishing the tension of the springs K, by turning the gears 7 in one direction or the other, the fabric or stuff may be acted upon more or less strongly, the braking action, due to the friction of the axles A in their boxes

55 or bearings, being greater or less. The yielding or elastic and adjustable suspension of the workers by their axles is thus a very important improvement, since it permits a regulated working for all kinds of stuff or material.

60 The new or improved system of contact demands—or at least it is most useful—that there should be in connection with it a means of regulating with great precision the contact of the workers with the fabric. To provide such

65 a means the following arrangement has been devised:

Referring to Fig. 1, slides E E' are supported

in ways or guides D' on each side of the machine-frame and adjusted simultaneously in opposite directions by means of the pinion D, 70 meshing with the racks L L' on the ends of said slides. These slides carry the fabric-guides (the rollers b' b'', supported by brackets c' c'' on the slides E E', as shown) over which the fabric is stretched when acted on by

75 the workers, so that by moving the slides E E' the said fabric is adjusted simultaneously toward or away from the workers 1. The guides b' on one side of the carriers B' B² B³ B⁴ are movable with the slide E, and the guides

80 b'' on the opposite side are movable with the slide E', so that all the guides move toward or away from the workers 1, according to the direction in which the pinion D is turned.

In the drawings the yielding or elastic support for the workers or napping-cylinders is formed on each carrier B' B² B³ B⁴ of a single spring at each end of the carrier. The invention is, however, not limited to the use of a single spring, although this constitutes a special feature of our invention; but it includes the use of the elastic or yielding supports generally, irrespective of the number and arrangement of the springs or the precise mechanical expedient employed.

95 We claim—

1. In a napping-machine, a rotatory carrier provided with yielding or elastic bearings for the working or napping cylinders thereon, and having such cylinders journaled in said bearings and rotated by contact with the fabric to be napped, substantially as described.

100 2. In a napping-machine, a rotating carrier provided with yielding or elastic bearings and brakes for the working or napping cylinders thereon, and having such cylinders journaled in and acted on by said bearings and brakes, said cylinders being rotated by contact with the fabric against the yielding resistance due to the braking action, substantially as described.

105 3. In a napping-machine, and in combination with a set of workers or napping-cylinders rotated on their carrier by contact with the fabric and the rotating carrier for said cylinders, the bearings and brakes for said workers, composed of a confined block outside the axle of the worker, a movable block out of contact with the former and arranged on the opposite side of said axle, and a spring for

110 pressing the movable block against the said axle, substantially as described.

115 4. In combination with a rotating carrier provided with divided boxes or bearings for the workers thereon, a set of workers having

120 their axles journaled in said boxes or bearings, and a curved leaf-spring for each end of the carrier, in the form of an endless band surrounding the axis of the carrier and forming an elastic support common to the boxes of the

125 set, substantially as described.

130 5. The series of carriers and their respective working or napping cylinders mounted on said carriers, in combination with the slides

having the racks and pinions for adjusting them simultaneously in opposite directions, and the guide-rollers mounted in brackets on said slides, substantially as described.

5 6. The combination, with the workers and their revolving carrier, of the boxes or bearings for the axles of said workers, the springs, and the screw-nuts for adjusting the spring-tension, substantially as described.

In testimony whereof we have signed this 10 specification in the presence of two subscribing witnesses.
